TIME SWITCH

Benjamin Perrone, Woodside, and Frank Santoro, New York, N. Y.

Application September 22, 1932
Serial No. 634,268

4 Claims. (Cl. 200—39)

This invention relates to time switches for opening and closing the circuits at a predetermined time of radio receiving sets, electric signs, electric heating devices, etc. etc.

5 One of the objects of the invention is to provide a clock with a pair of alarm releases, one to close the circuit and the other to open same at predetermined times.

Another object of the invention is to provide 10 means whereby the alarm release levers or other means employed for operating the clock circuit making and breaking switch is held out of effective relation with the said switch in order to permit the circuit breaking operating lever to function immediately after the circuit has been closed, if so desired.

Still another object of the invention is to provide 20 an exterior switch which may be closed at will so that the clock may be detached or removed from the circuit and used with another device.

Another object is to produce a device of the character described in which the maximum simplicity of construction and operation is secured.

Other objects and advantages will appear as 25 the nature of the improvements is better understood, the invention consisting substantially in the novel arrangement and co-relation of parts herein fully described, and illustrated in the accompanying drawings, wherein similar reference 30 characters are used to describe corresponding parts throughout the several views, and then finally pointed out and specifically defined and indicated in the appended claims.

The disclosure made the basis of exemplifying 35 the present inventive concept suggests a practical embodiment thereof, but the invention is not to be restricted to the exact details of this disclosure, and the latter, therefore, is to be understood from an illustrative, rather than a restrictive standpoint.

The inventive idea involved is capable of receiving a variety of mechanical expressions, one of which, for the purpose of illustration, is shown in the accompanying drawings in which

45 Figure 1 is a fragmental front view in elevation of a radio receiving set showing our improved timing switch or clock connected thereto.

Figure 2 is a front view of the clock mechanism with the dial removed.

50 Figure 3 is a top plan view thereof.

Figure 4 is a side elevation thereof partly in section looking from the left of Figure 2.

Figure 5 is a fragmental top plan view of the circuit making release arm operated to close the 55 circuit.

Figure 6 is a sectional view taken on line 6—6 Figure 2, but showing the switch after it has been operated to close the circuit and

Figure 7 is a diagrammatic view showing the electric circuit.

Referring now to the drawings in detail 10 indicates the clock mechanism of an ordinary alarm clock, which includes the usual spring operated gear wheel 11 which imparts rotary movement to a shaft 12 which carries the minute hand 13. A gear 14 in mesh with a pinion 15 on the shaft 12, carries a pinion 16 which is in mesh with a gear 17 having a sleeve 18 to which the hour hand 19 is secured. The pinion 16 is also in mesh with a second gear 20 which forms a part 65 of the releasing means of the usual alarm mechanism of the clock, and is rotatably mounted on a shaft 21. The shaft 21 has mounted thereon a hand 25 to the rear of which there is secured to the shaft 21 a disk 26 provided with a projection 27 riding on the end surface of a sleeve 28 integral with the gear 20. The said projection 27 holds the gear 20 against a spring arm 29. 70

A gear 30 which is an exact duplicate of the gear 20 is rotatably mounted on a shaft 31 which is provided with a hand or pointer 32. The gear 30 is driven by means of a pinion 33 secured to a gear 34 in mesh with the pinion 15. Like the gear 20 the gear 30 is held against a spring arm 35 by means of a projection 36 riding on the end surface of a hub or sleeve 37 on the said gear 30. Both of the spring arms 29 and 35 are secured 75 to the front plate 38 of the clock mechanism casing as at 39 and 40 respectively.

80 Our invention is shown as applied to radio receiving sets 45, but it may be just as readily applied to many other electrically operated devices. If for instance it is desired that the radio play for a duration of two hours, say between the hours of 7 and 9, the hand 25 is set at 7 (see Fig. 1) and the hand 32 is set at 9. When the hands 13 and 19 point to seven o'clock, the edge 50 of the cam cut out 51 will be free of the projection 27 permitting the spring arm 29 to move the gear outwardly and straighten itself out to assume the position shown in Fig. 5. In doing so 85 a lip or projection 52 on the said spring arm 29 will actuate a segment 53 pivoted at 54 to rotate downwardly. A spring 55 completing the downward movement after the segment has moved or rotated beyond a given point. The segment 53 which is made of any suitable electric insulating material, carries a metallic pin 56 which completes the circuit by contacting with the terminals 57 and 58 connected to terminal pins 59 and 100

105 Figure 5 is a fragmental top plan view of the circuit making release arm operated to close the circuit.

60 by means of lead wires 61 and 62. Insulating blocks 63 insulate the said pins from the rear plate 64 of the clock casing. The terminals 57 and 58 are carried by an insulation block 65 in the front plate 38.

5 The free end 70 of the lever 29 carries a roller 71 which when the said lever 29 snaps forwardly, rides on the under surface of an inclined plane 72 as the horizontal center line of the said roller 72 is below the top rear edge of the said inclined plane thus forcing the end of the lever with its projection 52 downwardly and holding the projection in the path of the segment 53 until the forward movement of the said lever is completed.

10 15 The roller 71 then rolls lands on top of the forward end of the inclined plane thus the ledge or projection 52 is high enough to be out of the path of segment 53. Should the lower spring lever 35 be actuated to break the circuit before the upper lever has been again pushed rearwardly by the action of the cam 51 on the sleeve 28 but while it is moving rearwardly, projection 52 will be held out of the path of the segment 53 by riding on the upper surface of the inclined plane until at the end of rearward movement, the projection again moves down to its original position ready to again engage the segment. The construction and action of the lower lever 35 is exactly the same as that of the lever just de-

30 35 scribed and the roller 71a carried thereby rides forwardly on the top surface of an inclined plane 72a and returns on the undersurface thereof as indicated in Figure 6, the actuation of the said lever being accomplished by a cam and a projection carrying disk exactly the same as the disk and cam 26 and 51 above described.

40 45 In order that the clock 10 may be disconnected from any device which it is operating or controlling, we provide a plug 80 for engaging the terminal pins 59 and 60, which plug is provided with a switch 81 (see Fig. 7) which may close the circuit and short circuit the line before reaching the terminals 57 and 58, thus permitting the current to flow from its source 82 through a lead line 83 thence through the switch to which it is connected and thence through a terminal 84 lead wire 85 to the radio or other device and back through a lead wire 86 to the source 82.

50 55 From the foregoing, it will be seen that we have provided a simple yet efficient time switch adapted to make and break the current in whatever electrical device it is used, and furthermore the said switch or clock being adapted to be disconnected from the device with which it is used and connected to any other device to be operated.

Having described our invention what we claim as new and desire to secure by Letters Patent is:

60 1. In combination with an alarm clock, hav-

ing a pair of slidable alarm release gears, a spring lever controlled by each of the said gears, a pair of electric terminals in electric circuit, a pivotally mounted arm, a contact pin thereon, a projection on each of the said levers for engagement with the said arm to rotate same about its pivot to engage or disengage the terminals when the gears are slid to release the spring, a roller on each of the said levers, and a plane so arranged with respect to the rollers as to lift the lever projections out of the path of the arm after the said arm has been so rotated.

2. In combination with an alarm clock having an upper and lower slidable alarm releasing gear, a spring lever controlled by each of the said gears, a pair of electric terminals in electric circuit, a pivotally mounted spring pressed segment, a metallic contact arm carried by the said segment, a projection on each of the said levers for alternate engagement with the said segment to swing same about its pivot to close and open the circuit when their respective gears are slid forwardly, a roller on each of the levers, and a plane so arranged with respect to the rollers as to lift the respective lever projections out of the path of the arm after the said lever has been released by the gear.

3. In combination with an alarm clock having an upper and lower slidable alarm releasing gear, a spring lever controlled by each of the said gears, a pair of electric terminals in electric circuit, a pivotally mounted spring pressed segment, a metallic contact arm carried by the said segment, a projection on each of the said levers for alternate engagement with the said segment to swing same about its pivot to close and open the circuit when their respective gears are slid forwardly, a roller on each of the levers, a plane so arranged with respect to the rollers as to lift the respective lever projections out of the path of the arm after the said lever has been released by the gear, and a switch in electric circuit with the terminals as and for the purpose specified.

4. In combination with an alarm clock, having a pair of slidable alarm releasing gears, a spring lever controlled by each of the said gears, a pair of electric terminals in electric circuit, a pivotally mounted arm, a contact pin thereon, a projection on each of the said levers for engagement with the said arm to rotate same about its pivot to engage or disengage the terminals when the gears are slid to release the spring, and a plane for each of the levers, the said planes being so arranged with respect to the levers as to lift the lever projections out of the path of the arm after the said arm had been so rotated.
